UNITED STATES PATENT OFFICE.

HENRY C. WEEDEN, OF BOSTON, MASSACHUSETTS, ASSIGNOR TO PHILLIPS
& WEEDEN, OF SAME PLACE.

FLUSHING APPARATUS FOR TANKS.

SPECIFICATION forming part of Letters Patent No. 274,156, dated March 20, 1883.

Application filed October 25, 1882. (No model.)

To all whom it may concern:

Be it known that I, HENRY C. WEEDEN, of Boston, in the county of Suffolk, of the State of Massachusetts, have invented a new and useful Improvement in Flushing Apparatus for Tanks; and I do hereby declare the same to be described in the following specification and represented in the accompanying drawings, of which—

10 Figure 1 is a top view, and Fig. 2 a longitudinal section, of a tank provided with my invention, the nature of which is defined in the claim hereinafter presented, its object being to gradually close the valve of a water-
15 closet or urinal tank after the raising of such valve from its seat, such being in order for a sufficient quantity of water to flow from the tank, to effect, as occasion may require, the flushing of the water-closet, or the urinal or
20 series of urinals.

In the drawings, A denotes the tank, whose induction-tube (not shown) is to be supposed, as usual, to be supplied with a cock, and with a float thereto, for closing it when the water
25 in the tank may have attained its normal altitude.

Leading out of the tank is an overflow-pipe, B, which opens into the discharge-pipe C or flushing-educt of the tank, immediately below
30 the top thereof, on which is a valve-seat, a. A valve, D, rests on the said seat, and is provided with a stem, b, to slide vertically in a guide, c, extending diametrically across the seat. The educt C is to lead to a water-closet
35 bowl or to a urinal or a conduit connecting one or more of such urinals, the same being so that the water discharged from the tank may flush the said bowl or urinal or urinals.

Over the valve and attached to a stem, d,
40 connected with the valve, and arranged concentrically with such stem, is a cup or bowl, E, open at top, the said stem d at its upper end being by a short chain, e, connected with the shorter arm of a slotted or open lever, F,
45 arranged over the tank, and within another such lever, G, both levers being fulcrumed on a shaft, H, supported by a bracket, I.

On the lever F is a spherical weight or ball,
K, which is adapted to roll lengthwise on the
50 said lever, from one to the other of two abut-

ments or stops, h i, extending upward therefrom, as shown. The front abutment, i, has a projection, k, to extend over the end portion, l, of the open lever G, in manner as represented. The said end portion, l, is of sufficient thickness or size to cause, by its weight and that of the rest of the shorter arm of the lever G, such shorter arm to overbalance the longer arm of such lever and the weight of the wire thereof, in order for the shorter arm by its weight to 60 depress the lever into the position shown in Fig. 1.

To the rear or longer arm of the lever G a wire, m, connected directly or indirectly with the water-closet handle, is attached. On pulling up such handle the longer arms of both levers F and G will be depressed, and the valve D, with the cup E, will be raised relatively to the valve-seat a, and the ball K will, through the action of gravity, roll upon the 70 lever F from the abutment i to the abutment h, the cup or bowl being filled with water. On the handle being dropped, the lever G will, by its heavier arm, be at once returned to its former position—viz., that shown in Fig. 1; but 75 the lever F by the ball K will be prevented from returning, and will hold up the cup E filled with water until the water in the tank may descend sufficiently below the top of the cup for the weight of the cup and its load to 80 overcome the power of the ball, to keep the lever F from returning to its position as shown in Fig. 1. On the cup being depressed, the valve will be closed and the ball will roll from the abutment h to the abutment i, the projection k resting upon the part l.

From the above it will be seen that when the valve is closed the levers are in positions as shown in the drawings; also, that on pulling up the handle of the water-closet so as to 90 pull downward the wire m, both levers will be tilted backward, the ball will roll from the abutment i to the abutment k, the valve will be raised off its seat, and the cup E, full of water, will rise with the valve, and by the ball 95 will be held from falling until the water in the tank may have descended sufficiently for the weight of the cup and its load to cause the valve to fall and the lever F to be tilted to the position shown in Fig. 1, the lever G having

previously been tilted back, so as to offer no hindrance to the fall of the cup and the valve. While the valve may be kept off its seat water will be discharged from the tank. In case 5 of leakage of the induction cock or valve, the water due to such will escape by the over-flow-pipe B. The head of water in the tank will keep the valve D closed upon its seat while the ball K may be resting against the 10 abutment i.

I claim—

For use with the tank and its eduction-valve, in manner as explained, the combination of the bowl E, the open weighted lever G, the ball K, and the open lever F, having the abutments *h i*, and projection *k*, all being arranged, applied, and to operate substantially as set forth.

HENRY C. WEEDEN.
